UNITED STATES PATENT OFFICE.

PASCUAL M. DIAZ, OF SAN ANTONIO, TEXAS, ASSIGNOR TO MERGENTHALER LINOTYPE COMPANY, A CORPORATION OF NEW YORK.

MOLD FOR TYPOGRAPHICAL CASTING-MACHINES.

1,092,142.

Specification of Letters Patent.

Patented Apr. 7, 1914.

Application filed August 14, 1913. Serial No. 784,663.

To all whom it may concern:

Be it known that I, PASCUAL M. DIAZ, a citizen of the United States, residing at San Antonio, in the county of Bexar and State of Texas, have invented certain new and useful Improvements in Molds for Typographical Casting-Machines, of which the following is a specification, reference being had therein to the accompanying drawing.

10 My invention relates to typographical machines, as for instance such as are illustrated in Letters Patent of the United States to O. Mergenthaler, No. 436,532, wherein a slug or Linotype is cast in a slotted mold 15 against a matrix line presented in operative relation to one side thereof.

More particularly, it relates to the mold itself, and is designed to provide a construction whereby its dimensions may be readily 20 altered to adapt it to the production of slugs of different length and thicknesses, as it will appear from the subsequent detailed description.

In the accompanying drawings, I show 25 my invention in preferred form and by way of example, and as applied to the particular style of machine already mentioned. However, many variations and alterations may be made therein, and in its mode of 30 adaptation, which will still be comprised within its spirit. Also, it may similarly be applied to type-casting machines, etc., or to any form of typographical machine designed to produce type, dies, or matrices, as 35 well as the slugs herein alluded to. Generally speaking, I desire it to be understood that I do not limit myself to any specific form or embodiment, except in so far as such limitations are specified in the claims.

40 Referring to the drawings: Figure 1 is a view of a portion of the mold disk, etc., of a Linotype machine, having my improved mold applied thereto; Fig. 2 is a similar view of the mold, illustrating a different adjustment thereof; Fig. 3 is a sectional view on the line 3-3 of Fig. 1; Fig. 4 is a sectional view on the line 4-4 of Fig. 1; Fig. 5 is a sectional view on the line 5-5 of Fig. 2; Fig. 6 is a perspective detail illustrating the 45 mode of connection of the liner to the cap; Fig. 7 is a transverse sectional view illustrating different sizes of liner; and Fig. 8 represents the form of slug produced by my improved devices.

55 As is usual in machines of this character,

an assembled line of matrices X is presented between the jaws Y in operative relation to the slotted mold carried by the mold wheel Z. In this instance, the mold comprises the body portion A constituting the lower wall, 60 the cap piece B constituting the upper wall, and the two end portions C and D constituting the end walls and contacting with and serving to support the cap piece. The mold proper is ordinarily less in length than the 65 distance between the portions C and D, its extent and that of the slug produced therein being the distance between the end wall C and the liner E, which latter is made adjustable to adapt the mold to the required 70 dimensions. To this end, the lower face of the cap B is formed with a plurality of transverse projecting ridges B¹ and intervening spaces B², and the liner E is provided with 75 projecting ribs E² formed to enter and engage the selected spaces B² of the cap portion and thus hold the liner in the desired relation thereto. When the mold proper is thus constituted, the idle portion of the slot between the liner E and the end portion D 80 may be temporarily filled with type metal, in the manner well understood in the art. The slug S (Fig. 8) produced in the mold will be formed with a series of depressions and ribs corresponding to the ridges B¹ and 85 intervening spaces B² of the cap B. When the parts are in adjusted position, the end pieces C and D are forced into close relation to the body portion A by springs G carried by the mold wheel Z, and the cap B is held 90 firmly in position by the screws H similarly carried by the mold wheel.

The width of the mold slot is governed 95 by the vertical position of the end pieces C and D, and in order to effect the necessary adjustment thereof, I provide the rotatable graduated cams F contacting therewith and carried by the mold wheel, in such manner that they may be turned at will for width adjustment. I also provide a plurality of 100 liners E of different thicknesses to correspond to the several width adjustments, and in Fig. 7 I illustrate two such liners designed for the production of slugs of widely different thickness.

105 As previously stated, the length of the mold proper depends upon the location of the liner E, and in order that this position may be varied substantially at will with reference to the body portion A, my arrange- 110

ment contemplates two distinct means of adjustment. The first means are those already described, namely, the ribs E² on the liner, which may be engaged with any desired spaces B² on the cap, this adjustment, however, being limited by the necessary separation of the respective ribs and spaces, which we will say for example cannot be less than a certain predetermined amount, as indicated by the longer or principal scale marks designated by the numerals on the scale J. In other words, due to the necessities of construction, it may be assumed that the minimum adjustment of the liner E with reference to the cap B is that corresponding to the distance between two of the principal scale marks, which may be taken as the unitary capability of these adjusting means. Thus in Fig. 1, the liner E is shown as adjusted to the scale mark 8, and it, of course, may be moved in either direction, say to the point 9, but it cannot be moved to a minor or intermediate scale mark, such as 8½. Therefore to secure the minor as well as the principal adjustments that may be desired, I provide the second form of adjusting means, which enable the longitudinal setting of the cap B with reference to the end pieces C and D. These means comprise the transverse grooves B³ near the end of the cap B, arranged to engage the transverse ribs C³ on the end piece C, the grooves B³ and ribs C³ being respectively separated to an extent sufficient to give the half-unit adjustment when desired. Thus in Fig. 1 the two central grooves B³ are shown in engagement with the ribs C³, whereas in Fig. 2, the two extreme grooves are shown in engagement with the ribs, this difference in position being sufficient to move the liner into registration with the scale mark 8½. It will thus be noted that the end pieces C and D not only serve to adjust the mold cap B toward and away from the body portion A, in order to vary the width of the mold slot, but in addition serve to maintain the mold cap B in its different longitudinally adjusted positions.

It will be seen that due to these combined means I am enabled to secure substantially every variety of length adjustment that may be desired, the unit adjustment being preferably effected by the relation of the liner to the cap, and the half-unit adjustment by the relation of the cap to the end piece. In order to secure the correct fore and aft relation of the cap to the mold, the end of the cap is formed with the short longitudinal recesses B¹⁰ adapted to engage the short longitudinal ribs C¹⁰ and D¹⁰ on the respective end pieces in any adjusted position of the cap.

As already stated, I have shown my invention only in preferred form and by way

of example and as applied to a linotype machine, but many modifications and changes in its construction and mode of adaptation will suggest themselves to those skilled in the art without departure from its scope.

Having thus described my invention, its construction and mode of operation, what I claim and desire to secure by Letters Patent of the United States is as follows:

1. A slotted mold comprising upper and lower walls, one adjustable relatively to the other lengthwise of the slot, and a part adjustable relatively to said walls lengthwise of the slot and constituting one of the end walls of the mold proper.

2. A slotted mold comprising a body portion, a cap portion adjustable relatively thereto lengthwise of the slot, and an intermediate liner adjustable relatively to the cap portion lengthwise of the slot.

3. A slotted mold comprising a body portion, a cap portion, and an intermediate liner attached to the cap portion and adjustable relatively thereto lengthwise of the slot, the said cap portion being shiftable lengthwise of the slot to vary the adjustment of the mold proper as determined by the liner.

4. A slotted mold comprising a body portion, a cap portion, and an intermediate liner, the said cap portion and liner being both adjustable lengthwise of the slot, one according to a given typographic unit and the other according to a fraction of such unit.

5. A slotted mold comprising a body portion, a cap portion formed on its inner face with projecting ribs whose separation corresponds to a typographic unit, and an intermediate liner recessed to receive the projecting ribs of the cap portion and adapted to be set in different positions thereon, the said cap portion being adjustable lengthwise of the slot according to a fraction of such typographic unit.

6. A slotted mold comprising a body portion, a cap portion formed on its inner face with projecting ribs lying within the mold slot and whose separation corresponds to a typographic unit, and further formed exterior to the mold slot with recesses whose separation corresponds to a fraction of such unit, a liner recessed to receive the projecting ribs of said cap portion and constituting the end wall of the mold proper, and a part provided with ribs to enter the exterior recesses of said cap portion and constituting the other end wall of the mold proper.

7. A slotted mold comprising a body portion, a cap portion, an intermediate liner attached to the cap portion and adjustable relatively thereto lengthwise of the slot, the said cap portion being shiftable lengthwise of the slot to vary the adjustment of the

mold proper as determined by the liner, and means for holding said cap portion in its adjusted position.

8. A slotted mold comprising a body portion, a cap portion, an intermediate liner attached to the cap portion and adjustable relatively thereto lengthwise of the slot, the said cap portion being shiftable lengthwise of the slot to vary the adjustment of the mold proper as determined by the liner, and means for holding said cap portion in its adjusted position, the said means constituting one of the end walls of the mold.

9. A slotted mold comprising a body portion, a cap portion, and end portions C and D constituting the opposing end walls of the mold slot upon which the cap portion is supported, together with means for adjust-

ing the end portions to vary the width of the mold, and the said cap portion being adjustable relatively to both end portions to vary the length of the mold.

10. A slotted mold comprising a body portion, a cap portion adjustable relatively thereto lengthwise of the slot, and common means for moving the cap portion toward and from the body portion to vary the operative width of the mold slot and for locking the said cap portion in its longitudinally adjusted position.

In testimony whereof I have affixed my signature in presence of two witnesses.

PASCUAL M. DIAZ.
